CLAIM

The ornamental design for a furniture leg tip, as shown and described.

DESCRIPTION

FIG. 1 is a front, top perspective view of a furniture leg tip, showing my new design;

FIG. 2 is a front, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the furniture leg tip that form no part of the claimed design.
